FORREST L. CANTRALL, OF LIKLEY, CALIFORNIA, ASSIGNOR, BY MESNE ASSIGNMENTS, TO ENGINEERING SPECIALTIES COMPANY, OF SAN FRANCISCO, CALIFORNIA, A CORPORATION OF CALIFORNIA.

AUTOMOBILE ENGINE STOP.

Application filed January 3, 1921. Serial No. 434,621.

To all whom it may concern:

Be it known that I, FORREST L. CANTRALL, a citizen of the United States, and a resident of Likley, Modoc County and State of California, have invented a new and useful 5 Automobile Engine Stop, of which the following is a specification.

My invention relates to means for automatically stopping the operation of an automobile engine.

An object of the invention is to provide means, operating automatically, for interrupting the spark of an automobile engine so that when the driver is away from the 15 car, the engine cannot be left running.

The invention possesses other objects and features of advantage, some of which, with the foregoing will be set forth in the following description of the preferred form of 20 my invention which is illustrated in the drawings accompanying and forming part of the specification. It is to be understood that I do not limit myself to the showing made by the said drawings and description, 25 as I may adopt variations of the preferred form within the scope of my invention as set forth in the claims.

Referring to the drawings; Figure 1 is a 30 plan view of my engine stop and portions of the automobile upon which it is applied. Electrical connection and circuits are shown in diagram. Fig. 2 is a vertical sectional view thru a portion of the engine stop casing. The plane of section is indicated by

35 line 2—2 of Fig. 1. The position of parts is that in which the spark circuit is short circuited. Fig. 3 is a vertical section similar to Fig. 2 but showing the parts in the position normally assumed during the 40 operation of the automobile. Fig. 4 is a horizontal sectional view, the plane of section being indicated by the line 4—4 of Fig. 2.

Owners of automobile delivery trucks 45 have found that a large saving in fuel could be effected if the drivers could be induced to shut off the engine when the vehicle is left standing during deliveries. This has been found to be impracticable and it is therefore one of the objects of my invention to provide a means of automatic control, the operation of which is initiated 50 when the transmission system of the car is rendered inoperative, as it necessarily must

be when the car is brought to rest without stopping the engine. In the transmission 55 system, I include change gears, clutch and other mechanisms between the engine and the driving axle.

In terms of broad inclusion the structure of my device comprises a block in which are 60 arranged a cylinder containing a piston, a cylinder comprising a dash pot, and a chamber containing a valve. The valve chamber is connected to the intake manifold between the butterfly valve and the 65 cylinders and the valve is opened and closed with movement of the gear shift lever. Opening the valve places the piston cylinder in communication with the intake manifold so that the partial vacuum therein is 70 utilized to move the piston, which operates a circuit closing and opening mechanism for controlling the spark circuit. The piston is connected to the dash pot piston and its movement is controlled thereby. If 75 the engine of the car is left running, the gear shift lever must be brought to neutral position to stop the car. Such movement of the lever effects a connection of the manifold to the cylinder containing the 80 piston, which operates the circuit closing and opening mechanism, and within a predetermined interval, the spark is discontinued and the engine stopped, upon which the piston and circuit closing and opening 85 mechanisms return to first position which restores the spark circuit.

In detail terms, my invention comprises a block 2 provided with lugs 3 for connecting the block to the frame 4 of the automobile. The block is formed with three cylinder chambers 6, 7 and 8, the middle one, 7, having a rotary valve 9 disposed therein. A lever arm 11 fixed on the valve stem is connected by link 12 to the gear shift lever 13. The valve is formed with an annular groove 14 in register with the port 16 in the side wall of the block which is in communication by means of conduit 17 with the intake manifold 18 of the engine 19. A passage 21 in the valve opens at one end in the annular groove and the other end is registered with the port 22, leading into the bottom of the chamber 8, when the lever 11 is in its central position which occurs when the gear shift lever is moved to 100 105

neutral position. Movement of the gear shift lever out of neutral, turns the valve to cover the port 22.

Arranged in the chamber 8 is a relatively long piston 23 formed hollow as shown and normally resiliently retained in the upper end of the chamber by the coil spring 24. Journalized in the stud 26 extending upwardly from the block is a short shaft 27 slightly longer than the stud is thick, and provided with a short pin 28 extending from each end. Twin rocker arms 29 are mounted on the pins, one on each side of the stud. A link 31, at one end, pivotally connected, preferably by a ball joint, to the piston 23, is pivoted at the other end between the rocker arms on one side. On the other side, the rocker arms are similarly connected by link 32 with dash pot piston 33 arranged in chamber 6, the lower portion of which contains a quantity of oil.

The lower end of the link 32 is provided with a passage 34 opening on the under side of the piston and also on the side of the link within the piston in the port 36. A sleeve 37 surrounding the link and formed with a short spiral slot 38 overlying the port 36, provides means for adjusting the size of the by-pass passage. The sleeve extends to the top of the link and is provided with a recessed flange 39 to facilitate turning. Movement of the piston 23 is thus timed by the rate of flow of the oil thru the passage 34 from one side of the piston to the other.

Pivotally mounted on each pin 28 on the outside of each rocker arm is a lever arm 41, the end of which is connected by spring 42 to the far end of the adjacent rocker arm. The two levers 41 are preferably formed originally in one piece connected by an arm 43. This piece is then folded to bring the levers into alignment and parallelism, the arm forming an arch connecting the two levers and overlying the twin arms 29 when assembled. The center of the arch is provided with a contact point 44, adapted to engage the stud 46 fixed in and insulated from the hood 47 which houses the top of the block and is held thereon by a nut on the threaded end 48 of the stud 26. The stud 46 is connected by conductor 49 with the spark circuit 51 between the generator or battery 52 and the distributor head 53. The arms 41 thus comprise a switch mechanism for shorting the spark circuit thru the conductor 49 and the instrument itself, when the contact 44 engages the stud 46, and freeing the circuit when the contact disengages the stud.

60 Operation.

The engine of the car is assumed to be running. The parts are in the position shown in Fig. 3, the circuit thru the switch mechanism and conductor 49 being interrupted. If the car is stopped and the engine

left running the gear shift lever must be brought to neutral position. This turns the valve 9 to connect the manifold with the chamber 8, and the vacuum in the manifold sucks the piston 23 downwardly at a speed determined by the dash pot adjustment. After a short movement of the piston, the springs 42 pass the axis of the pivot pins 28, exerting a rapidly accelerating resilient pressure on the switch arms 41, snapping them abruptly downwardly and contacting the point 44 with the stud 46. The parts are now as shown in Fig. 2, and the ignition circuit 51 is shorted, interrupting the spark and stopping the engine. With the stopping of the engine, the vacuum is released, and under the influence of the spring 24, the piston rises, carrying up the spring 42 which, upon passing the axis of the pivot pins, snaps the arms 41 back to first position breaking the short circuit and reestablishing the ignition circuit. The dash pot mechanism is adjusted to permit the piston 23 to complete a stroke in, say 30 seconds, so that in starting there is ample time for the driver to crank his car, get in, and shift his gears, before the spark is again interrupted. With the shifting of the gears, the valve 9 is turned to close the port 22 and the device is then inoperative until the gear shift lever is again moved to neutral, when the same cycle of operations occur as before. It will be understood that during the 30 seconds required for the device to stop the engine, the delivery man may make many of his calls. Where the call is short, that is, within the adjusted limit, the engine will be running when he returns. The purpose of my invention however is to make it impossible to leave the engine running during absences from the car extending over periods long enough to involve objectionable waste of fuel.

It will be perfectly obvious from the foregoing that instead of the switch lever completing a short circuit in a grounded system, it may be connected in series with the ignition, and act as a make-and-break device therein.

I claim:

1. An attachment for automobile engines comprising a switch for interrupting the spark, means operating in both the closed and open positions of said switch for applying thereto a rapidly accelerated resilient pressure to throw the switch abruptly to the other position, and means effective when the transmission system of the automobile is inoperative for initiating the operation of said means.

2. An attachment for automobile engines comprising a switch for interrupting the spark, means operating in both the closed and open positions of said switch for applying thereto a rapidly accelerated resilient pressure to throw the switch abruptly to the

- other position, and means actuated by the vacuum induced in the engine for operating said switch throwing means.
3. An attachment for automobile engines, comprising a switch for interrupting the spark, means operating in both the closed and open positions of said switch for applying thereto a rapidly accelerated resilient pressure to throw the switch abruptly to the other position, vacuum controlled means for operating said switch throwing means, and means effective when the transmission system of the automobile is inoperative for connecting said vacuum controlled means to the intake manifold of the engine.
4. An attachment for automobile engines comprising a switch for interrupting the spark, means operating in both the closed and open positions of said switch for applying thereto a rapidly accelerated resilient pressure to throw the switch abruptly to the other position, vacuum controlled means for operating said switch throwing means, and means operatively connected to the gear shift mechanism for connecting said vacuum controlled means to the intake manifold of the engine.
5. An attachment for automobile engines comprising a switch for interrupting the spark, means operating in both the closed and open positions of said switch for applying thereto a rapidly accelerated resilient pressure to throw the switch abruptly to the other position, a piston connected to said switch throwing means, and means effective when the transmission system of the automobile is inoperative for subjecting said piston to the vacuum induced in the engine.
6. An attachment for automobile engines comprising a switch for interrupting the spark, means operating in both the closed and open positions of said switch for applying thereto a rapidly accelerated resilient pressure to throw the switch abruptly to the other position, a piston connected to said switch throwing means, means effective when the transmission system of the automobile is inoperative for subjecting said piston to the vacuum induced in the engine, and a spring for effecting the recovery of said piston.
7. An attachment for automobile engines comprising a switch for interrupting the spark, means operating in both the closed and open positions of said switch for applying thereto a rapidly accelerated resilient pressure to throw the switch abruptly to the other position, a piston connected to said switch throwing means, means effective when the transmission system of the automobile is inoperative for subjecting said piston to the vacuum induced in the engine, a spring for effecting the recovery of said piston, and means for timing the movement of said piston.
8. An attachment for automobile engines, comprising a switch for interrupting the spark, means operating in both the closed and open positions of said switch for applying thereto a rapidly accelerated resilient pressure to throw the switch abruptly to the other position, a vacuum controlled piston for operating said switch throwing means, a valve for controlling the application of engine induced vacuum to said piston, and means operatively connected with the gear shift mechanism for operating said valve.
9. An attachment for automobile engines, comprising a switch for interrupting the spark, means operating in both the closed and open positions of said switch for applying thereto a rapidly accelerated resilient pressure to throw the switch abruptly to the other position, a vacuum controlled piston for operating said switch throwing means, a valve for controlling the application of engine induced vacuum to said piston, a spring for effecting the recovery of said piston, and means operatively connected with the gear shift mechanism for operating said valve.
10. An attachment for automobile engines comprising a switch for interrupting the spark, means operating in both the closed and open positions of said switch for applying thereto a rapidly accelerated resilient pressure to throw the switch abruptly to the other position, a vacuum controlled piston for operating said switch throwing means, a valve for controlling the application of engine induced vacuum to said piston, a spring for effecting the recovery of said piston, means for timing the movement of said piston, and means operatively connected with the gear shift mechanism for operating said valve.
11. An attachment for automobile engines comprising, a piston, means operatively connected to the gear shift mechanism for controlling the application of engine induced vacuum to said piston, a rocker arm connected to said piston, a pivoted switch arm for interrupting the spark, and a tension spring connecting the rocker and switch arms so that each stroke of the piston shifts the spring to the opposite side of the switch arm axis.
12. An attachment for automobile engines comprising, a piston, means operatively connected to the gear shift mechanism for controlling the application of engine induced vacuum to said piston, a rocker arm connected to said piston, means for timing the speed of said piston, a pivoted switch arm for interrupting the spark, and a tension spring connecting the rocker and switch arms so that each stroke of the piston shifts the spring to the opposite side of the switch arm axis.
13. An attachment for automobile engines

comprising, a piston, means operatively connected to the gear shift mechanism for controlling the application of engine induced vacuum to said piston, a rocker arm connected to said piston, means for effecting the recovery of said piston, means for timing the speed of said piston, a pivoted switch arm for interrupting the spark, and a tension spring connecting the rocker and switch arms so that each stroke of the piston shifts the spring to the opposite side of the switch arm axis.

14. An attachment for automobile engines comprising, a piston, means operatively connected to the gear shift mechanism for controlling the application of engine induced vacuum to said piston, a rocker arm connected to said piston, means for controlling the speed of said piston, means for varying the effect of said controlling means, a pivoted switch arm for interrupting the spark, and a tension spring connecting the rocker and switch arms so that each stroke of the piston shifts the spring to the opposite side of the switch arm axis.

15. An attachment for automobile engines comprising a block formed with three chambers therein, a piston disposed in one of said chambers, timing means for controlling

the speed of said piston arranged in another of said chambers, a valve arranged in the third chamber and connected to the gear shift mechanism for controlling the connection of said piston chamber to the intake manifold of the engine, a rocker arm for connecting the piston to the piston timing means, and a switch for interrupting the spark operated by said rocker arm.

16. An attachment for automobile engines comprising a block formed with three chambers therein, a piston disposed in one of said chambers, timing means for controlling the speed of said piston arranged in another of said chambers, a valve arranged in the third chamber and operatively connected to the gear shift mechanism for controlling the connection of said piston chamber to the intake manifold of the engine, a rocker arm for connecting the piston to the piston timing means, a pivoted switch arm for interrupting the spark, and a tension spring connecting the rocker and switch arms so that each stroke of the piston shifts the spring to the opposite side of the switch arm axis.

In testimony whereof, I have hereunto set my hand.

FORREST L. CANTRALL.
